UNITED STATES PATENT OFFICE.

JOHN W. MONTAGUE, OF NEW YORK, N. Y.

DESIGN FOR TEXTILE FABRIC USED FOR DRAPERIES.

Application filed November 22, 1924. Serial No. 11,449. Term of patent 3½ years.

To all whom it may concern:

Be it known that I, JOHN W. MONTAGUE, a citizen of the United States, residing in the city, county, and State of New York, have invented a new, original, and ornamental Design for Textile Fabric Used for Draperies, of which the following is a specification, reference being had to the accompanying drawing, forming part hereof.

The figure shows a piece of fabric illustrating my new design.

I claim:

The ornamental design for textile fabric used for draperies as shown.

JOHN W. MONTAGUE.
